UNITED STATES PATENT OFFICE.

SAVIOUR MASTRONTONIO, OF NEW YORK, N. Y.

LUGGAGE CARRIER.

Application filed February 18, 1925. Serial No. 10,144.

This invention relates to luggage carriers, an object being to provide means whereby a bag, satchel, suitcase or the like may be conveniently carried without subjecting a 5 person to the weight of the carrier.

Another object of the invention is the provision of means for securing wheels or rollers to a carrier of the type mentioned whereby the latter will not interfere with carrying the suitcase or satchel in the ordinary manner, together with means for removably securing a handle to the carrier so that the latter may be readily transported in a manner to relieve the person carrying the bag. 10

15 of the weight of said bag.

Another object of the invention is the provision of a sectional extensible handle which may be removably attached to the carrier and placed within the same when 20 not in use.

With the above and other objects in view, the invention further includes the following novel features and details of construction, to be hereinafter more fully described, 25 illustrated in the accompanying drawings and pointed out in the appended claim.

In the drawings:—

Figure 1 is a view illustrating the invention in use.

30 Figure 2 is an enlarged fragmentary view partly broken away showing the manner of attaching the handle.

Figure 3 is a fragmentary view partly broken away showing the manner of attaching the wheels.

35 Figure 4 is a fragmentary plan view with parts in section.

Figure 5 is a fragmentary plan view showing a portion of a suitcase with the combined locking and handle attaching plate.

40 Figure 6 is a perspective view of a suitcase with the invention applied.

Referring to the drawings in detail wherein like characters of reference denote corresponding parts, the reference character 10 indicates a satchel or bag and 11 a suitcase, the invention being applied to both the bag and suit case. While carriers of this character are illustrated it is of course obvious 45 that the invention is applicable to carriers of other types.

In order to support the carrier there is located within the same along the bottom spaced reinforcing strips 12 while secured

to these strips as shown at 13 are outwardly 55 and oppositely extending arms 14, the latter forming axles for wheels or rollers 15. The wheels or rollers 15 are preferably provided with rubber tires 16.

The fastening means 13 comprises bolts 60 which extend through the arms 14 and through the bottom of the carrier into the reinforcing strips 12. Staples or cleats 17 also extend through the bottom of the carrier and engage the arms 14 and strips 12 65 so as to hold the arms rigid. The carrier may thus be supported by the wheels 15 for ready transportation.

In order to conveniently move the carrier there is provided a detachable handle 18. 70 This handle includes a plurality of curved sections 19 which are provided with threaded extensions and sockets 20 so that the sections may be detachably connected. One of these sections is threadedly engaged with 75 the stud 21 which is located within a socket 22 provided in a plate 23. This plate is pivotally secured to the carrier as shown at 24 and its free end has pivotally secured thereto as indicated at 25 a locking finger 80 26. This finger is provided at one end with a hook-shaped bill 27 which removably engages a staple 28, a finger piece 29 projecting from one end of the finger 26 whereby the latter may be readily manipulated. The 85 plate may be provided with a suitable lock 30 so as to prevent unauthorized opening of the carrier.

The inner section of the handle 18 is provided with an annular groove 31 which 90 is adapted to removably receive attaching lugs 32, one of which may be locked in place by means of a lock 33 so that the handle will be held against unauthorized removal. When the handle is not in use it 95 may be removed and placed within the carrier and the latter may be carried in the usual manner.

The invention provides exceedingly convenient means whereby a heavy or other carrier may be easily transported, in addition to means whereby the owner of the carrier may retain a grip on the latter without the necessity of supporting its weight and thus guard against theft.

100 The invention is susceptible of various changes in its form, proportions and minor details of construction and the right is here-

in reserved to make such changes as properly fall within the scope of the appended claim.

Having described the invention what is claimed is:—

A wheel mount comprising an arm adapted to extend outwardly from beneath the bottom of a wheel supported member, a

wheel carried by said arm, a reinforcing member upon the upper face of said supported member, and means extending through the supported member and engaging the arm and reinforcing member to secure the arm in position.

In testimony whereof I affix my signature.

SAVIOUR MASTRONTONIO.
